UNITED STATES PATENT OFFICE

2,434,616

PAPER FEED FOR WRAPPING MACHINES

William Hoppe, Longmeadow, Mass., assignor to
 National Bread Wrapping Machine Co., Springfield, Mass., a corporation of Massachusetts

Application February 13, 1946, Serial No. 647,224

1 Claim. (Cl. 93—2)

1

This invention relates to improvements in web feeding mechanisms for wrapping machines of the general type shown in my prior Patent 2,347,560, April 24, 1944. In this type of web feed the wrapper is supplied in the form of a continuous web, the leading end of which initially hangs down between the unwrapped article and an article carrier. A constantly rotating roll in fixed position has a friction surface so that whenever the movement of the article into the carrier or the subsequent movement of the carrier tends to draw out the wrapper the latter will be tightened around the roll and will be fed out without substantial strain on the article. This is particularly important where the article is easily deformed as in the case of a sliced loaf of bread. Before the wrapper is severed a second or draping roll is moved downwardly to tighten the wrapper around the rotating roll and cause the feeding out of a sufficient length of wrapper to form the proper initial amount for the wrapping operation upon the next succeeding article.

In the use of the mechanism of my prior patent it has been found that there is a tendency at certain stages in the movement of the carrier for the wrapper to exert an undesirable pull upon the article. This is due to the fact that, as the carrier starts to move, it initially approaches the rotating roll, causing the formation of slack which is subsequently taken up with a sudden pull on the wrapper. In accordance with the present invention this difficulty is avoided by giving a second function to the draping roll, causing it to move downwardly as the carrier starts to rise and then to move upwardly with the carrier although preferably at a slower rate. In this way formation of slack during the initial part of the carrier movement will be avoided and no sudden pull of the wrapper on the article can occur.

The invention will now be described with reference to the accompanying drawings, in which

Fig. 1 is a view of the wrapping mechanism, partly in median section, with the parts in the positions assumed as an article is being advanced into the carrier; and

Figs. 2, 3 and 4 are similar views showing successive stages in the wrapping operation.

Articles are fed into the machine along an upwardly inclined guideway 12 having side plates 13 by an intermittently actuated conveyor 14 having spaced flights 15. Located above this guideway are horizontal plates 17, 18 forming the floor of a wrapping and delivery channel. A carrier arm 19 is pivoted to the machine frame at 20 and has attached to it a depending arm 21 for

2

cam operation as described in Patent 2,347,560. At its outer end the carrier has an article supporting plate 26 which, as the carrier is oscillated by the cam, moves between an article-receiving position of Fig. 1 and an article discharging position of Fig. 4. Side folding plates 27 are shown mounted on the carrier as described in said patent.

The wrapper web *w* is fed from any desired source over a plate 28 near the end of which is located a feed roller 29 preferably having a rubber or other frictional surface and being driven continuously by suitable connections. Mounted at the ends of a pair of arms 30 is a second roller 31 set so as to come close to the roller 29 but preferably not close enough to press the web *w* against it. This roll is swung between its extreme positions of Figs. 3 and 4 by a link 32, rocker 33, adjustable crank 34, link 35, and a swinging arm 36 as fully described in Figs. 10 and 11 of the patent. The cam 37 by which this mechanism is controlled is, however, of a different shape from that in the patent and gives to the roll 31 a novel function in addition to that described therein as will be set forth below. The cutter 38 is preferably operated as in the patent and this and other parts there shown will not be further considered.

The novel operation of the roller 31 can best be considered in connection with a complete cycle of the mechanism for enveloping the article circumferentially in a wrapper. At the start of this operation the leading end of the web is hanging down between the carrier and the advancing article *a* as shown in Fig. 5 of the patent. As the carrier comes into line with the plate 12 the article is moved onto it by one of the flights 15, folding the lower end of the wrapper between the bottom of the article and the carrier plate 26 as in Fig. 1 of the present case. When, or slightly before, the article has been completely seated on the carrier the latter starts to rise. At the same time the roll 31 is lowered by its cam 37 at a rate sufficient to prevent any formation of slack in the wrapper between the article and roll 29 instead of remaining stationary as in the former case. Only a relatively slight lowering of the roll, substantially as shown in Fig. 2 is necessary, as the passage of the top of the rising article 50 above the roll prevents any further formation of slack. As the article passes onto the carrier and the roll 31 descends, the wrapper web is continually held tightly around the constantly rotating roll 29, so that the latter feeds the web forwardly by impositive frictional contact just

enough to supply the amount of wrapper needed in the progressive envelopment of the article without exerting any substantial strain on the latter.

Once the top of the article has passed the roll 31, the latter is raised by its cam, although preferably at a slower rate than the rise of the carrier, so that by the time the carrier reaches its discharge position of Fig. 3 the roll is in its initial or uppermost position adjacent the roll 29. The wrapper is at this time clamped between the two rolls 39 and 40 on the elevator and delivery channel respectively, and the roll 31 is lowered rapidly as in Fig. 4 to draw out the required length of wrapper for starting the next wrapping cycle without exerting any strain on the article. When the roll reaches its lower position the knife is operated as in the earlier case and the end of the web falls down in front of the feeding conveyor.

I claim:

The combination with a wrapping machine of the type having a carrier movable between an in-feeding and a delivery station, a constantly rotating frictional surfaced web feed roll located

5
10

adjacent the path of the carrier and between said stations, and a draping roll movable between the feed roll and the carrier, of mechanism constraining the draping roll for movement from an initial position adjacent the web feed roll towards the in-feeding station as the carrier moves away from it, whereby the formation of slack between the carrier and the web feed roll is prevented, then for movement in the same direction as the carrier to reduce the pull of the web on the article being wrapped, then for movement towards the in-feeding station to draw out a length of web, and finally for movement to its initial position.
